UNITED STATES PATENT OFFICE.

THOMAS SEABORN MORGAN, OF CHICAGO, ILLINOIS, ASSIGNOR TO
GWENDOLYN CATTELL MORGAN, OF CHICAGO, ILLINOIS.

STEAM-HEATING SYSTEM.

No. 820,809.

Specification of Letters Patent.

Patented May 15, 1905.

Application filed September 16, 1905. Serial No. 278,715.

To all whom it may concern:

Be it known that I, THOMAS SEABORN MORGAN, a citizen of the United States, residing at Chicago, in the county of Cook and State of Illinois, have invented new and useful Improvements in Steam-Heating Systems, of which the following is a specification.

This invention is a device or combination for creating and maintaining automatically a vacuum in a low-pressure steam heating apparatus. For various reasons well known in the art the maintenance of a vacuum in such apparatus is desirable.

The object of the present invention is to do this in an automatic and efficient manner, as will more fully appear from the following specification.

In the accompanying drawings, Figure 1 is an elevation illustrating the system. Fig. 2 is a diagram of a modification.

Referring specifically to the drawings, 6 indicates the boiler of a low-pressure steam-heating system, of which 7 is the flow and 8 the return pipes, leading to radiators (not shown) of any suitable kind. A vacuum steam-pump is indicated at 9 from the steam-cylinder 10, the exhaust from which passes by the pipe 11 to the flow-pipe 7.

12 is the suction-pipe, connected from the pump-cylinder 13 to the return-pipe 8 above the water-line of the boiler 6.

14 indicates a boiler feed-pump, the suction-pipe 15 of which is connected to the pipe 8 below the water-line of the boiler 6. This pump 14 is conveniently operated by direct connection by a rod 16 with the piston of the steam-cylinder 10.

17 indicates a small steam-generator, and 18 is a water-regulator which controls the supply of water from the pump 14 to the generator through the pipe 19. Steam generated in the boiler 17 is conveyed by a pipe 20 to the steam-cylinder 10 to operate the pump 9. The pump 14 also has a discharge-pipe 21 leading to the boiler 17.

Gas fuel for the boiler 17 is furnished through a pipe 22, and the flow or supply is controlled as follows: The diaphragm-valve 23 in the pipe 22 is connected by a pipe 24 to the return-pipe 8. A pressure inside said pipe or the heating system presses on the diaphragm of the valve 23 and holds the valve

open. The pipe 22 also has another diaphragm-valve 25, which is controlled by the temperature of the pipe 8 in the following manner: An inclosed cylinder 26, containing gasoline, ether, alcohol, or any other liquid having a low boiling-point, surrounds the pipe 8, and when the temperature of the pipe is raised the liquid volatilizes in the cylinder 26 and creates a pressure which is transmitted through a pipe 27 to the valve 25 and keeps the valve closed when the system is hot and open when it is cold. The supply of gas to the boiler 17 is thus controlled by both pressure and temperature. When the system is cold and there is an inside pressure therein, the valves 23 and 25 are both open, which permits the gas to flow through the pipe 22 to the burner 28 under the boiler 17, where it is ignited by a pilot-light 29, the supply-pipe of which is connected to the main 22 on the other side of the valves.

Steam generated in the boiler 17 passes through the pipe 20 and operates the pump 9, which exhausts air or water and reduces pressure in the heating apparatus, so that the flow proceeds until the desired heat is obtained. When the pressure is reduced to the desired extent, the valve 23 will close and the supply of fuel to the boiler 17, and consequently the operation of the pump 9, will be stopped. When the pressure rises, the valve will open and the pump may be started again; but when the system is hot the supply of fuel to the boiler 17 will be stopped by the valve 25, as above described.

Where a supply of electricity can be used to better advantage than gas, the arrangement shown in Fig. 2 can be installed. There a motor 30 is substituted for the generator 17 to operate the pump and the diaphragm-switches 23^a and 25^a for the valves 23 and 25.

It can be seen from the above that the pump operates only when needed, and then it works automatically in starting and stopping.

To prevent the escape of steam from the heating apparatus through the suction-pipe 12 of the air-pump, a diaphragm-valve 12^a is placed in said suction-pipe and is connected by a pipe 12^b to the cylinder 26, which surrounds the return-pipe of the heating system and which contains volatile liquid. When

the liquid in the cylinder becomes heated, the consequent pressure closes the diaphragm-valve 12^a in the suction-pipe and prevents the escape of steam through said pipe to the pump-cylinder 13.

5 What I claim as new, and desire to secure by Letters Patent, is—

1. In a steam-heating system, in combination, a vacuum-pump connected to the return-pipe of the system, and means to operate the pump controlled by the pressure, and also independently by the temperature, in the system.

2. In a steam-heating system, in combination, a vacuum-pump connected to the return-pipe of the system, a steam-generator connected to the pump, to supply steam thereto, and a fuel-supply to the generator controlled by the heat and pressure in the pipes of the system.

3. In a low-pressure steam heating system, in combination, a vacuum-pump drawing air therefrom, a boiler connected to the pump and supplying steam thereto to operate the same, and a fuel-supply to the boiler auto-

30 matically controlled by the degree of vacuum in the system.

4. In a low-pressure steam-heating system, in combination, a main boiler and circulation-pipes, a vacuum-pump drawing air from the circulation-pipes, an auxiliary boiler connected and supplying steam to the pump, to operate the same, and a feed-pump for the auxiliary boiler, connected to and operating with the vacuum-pump.

35 5. In a steam-heating system, in combination, a boiler having flow and return pipes, a vacuum-pump connected to the return-pipe, another boiler connected to said pump and arranged to supply power thereto, a fuel-supply to the latter boiler, and means automatically operated by the pressure in the system to control said supply.

40 In testimony whereof I have signed my name to this specification in the presence of 45 two subscribing witnesses.

THOMAS SEABORN MORGAN.
